UNITED STATES PATENT OFFICE.

FIELDING McCLUNG STARBUCK, OF WASHINGTON, DISTRICT OF COLUMBIA.

CARBURETER ATTACHMENT.

1,194,437.

Specification of Letters Patent. Patented Aug. 15, 1916.

Application filed September 26, 1915. Serial No. 792,612.

To all whom it may concern:

Be it known that I, FIELDING McCLUNG STARBUCK, a citizen of the United States, residing at Washington, in the District of Columbia, have invented a new and useful Carbureter Attachment, of which the following is a specification.

The present invention relates to improvements in carbureter attachments, one object of the invention, being the provision of means, by which a less volatile fuel, as for instance, kerosene oil, may be used as a primary starting and power giving fuel, in lieu of the less volatile fuel such as gasolene, it being possible with the present attachment to use the usual form of carbureter that is now employed in using gasolene, this particular structure providing a means by which the kerosene is adapted to be held in an insulating porous absorbent material and by which a resistance heating medium is connected in heating relation to such insulating and absorbent medium, to heat the oil to volatilize the same at the primary starting of the explosion engine.

A further object of the present invention, is the provision of means adapted to be connected in the air intake of a carbureter, adjacent to the spraying nozzle thereof, so that the fuel when injected therethrough by means of the priming means of the carbureter, will be directed upon an insulating and absorbent material, which constitutes a portion of an electric heating unit, the current passing through the same tending to volatilize the fuel so that the initial starting of the engine may be performed with the use of a less volatile fuel as kerosene oil.

A still further object of the present invention, is the provision of a tubular member composed of an absorbent material which is porous so as not to offer too great an obstruction to the passage of the carbureted air from the carbureter through the manifold of the engine and yet at the same time properly support the heating coil so that the kerosene contained therein will be properly volatilized at the initial starting of the engine.

With the foregoing and other objects in view which will appear as the description proceeds, the invention resides in the combination and arrangement of parts and in the details of construction hereinafter described and claimed, it being noted that changes in the precise embodiment of the

invention herein disclosed can be made within the scope of what is claimed without departing from the spirit of the invention.

In the drawings Figure 1 is a sectional view through a form of carbureter with the present invention applied in use. Fig. 2 is a longitudinal sectional view through the insulating and absorbent medium showing the resistance coil in operative relation thereto. Fig. 3 is an enlarged detail view of a modified form of the absorbent and heating medium.

Referring to the drawings, and more particularly to Figs. 1 and 2 thereof, C indicates the carbureter, which is provided with the air channel 1, in which is disposed the nipple or nozzle 2 of the fuel supplying means. Leading from the air channel is the manifold 3, which as clearly shown carries the present heating and absorbing medium 4, the details of which are clearly shown. This medium 4, consists of a tube 5, preferably of asbestos, or in fact any fiber that will absorb the fuel as the same is emitted from the nozzle into the lower end of the medium, thus permitting the saturation of the asbestos by capillary attraction, the resistance or heating coil 6 being disposed exteriorly of the asbestos tube, having one terminal 7 connected to and insulated from the manifold as at 8 while the other terminal 9 is connected to and insulated from the manifold as at 10. The tube 5 is preferably composed of sheets of asbestos or in fact any porous material that will permit of the passage therethrough without too great interference or impedance of the carbureted air, for the reason that the same is disposed at all times in the path of the inrush fuel even when the current is not passing through the heating coil. It will thus be seen, that when the priming charge is injected through the nozzle, that the same will be sprayed or atomized upon the absorbent tube, and that by capillary attraction the fuel will finally extend the full length of the asbestos tube. At this point, the resistance coil is energized by any well known means, so that the heat therefrom will volatilize the fuel absorbed in the tube, the explosion engine (not shown) being operated to draw the vapor and the air to conduct the desired carbureted air directly into the explosion chamber. After the engine is properly started from the initial volatilized and priming charge, the resistance medium is cut out and thereafter

the engine will operate directly by drawing in a carbureted air composed of the kerosene oil and air.

In the form of heating means shown in Fig. 3, the central pole or electrode 11 of the spark plug 12 has connected to its end, the metal connection or rod 13 whose lower end is connected at 14 to the lower end of the spiral resistance coil 15, the upper end of which is grounded to the coupling 15'. The asbestos tubular member 5' is wound around the rod and the spiral coil 15 is wound around the said tubular member 5'. The outer coupling 16 of this member is adapted to permit the attachment thereof at any desired point, or according to the construction of the carbureter upon which the present heating device is employed, it being essential, however, that the asbestos be placed in such a position as to receive the atomized spray of fuel from the nozzle or other fuel directing means of the carbureter.

What is claimed is:

The combination with the intake manifold of an explosive engine, of an electrical heating device for volatilizing liquid fuel, adapted to be arranged longitudinally in the path of fuel in passing from the carbureter to the cylinder, said heating device consisting of a tubular body of porous insulating material, into one end of which the fuel to be volatilized is projected, and a bare metal coil adapted to be included in an electrical circuit and arranged surrounding and coiled upon said body with its extremities connected with terminals located exteriorly of the manifold.

In testimony that I claim the foregoing as my own, I have hereto affixed my signature in the presence of two witnesses.

FIELDING McCLUNG STARBUCK.
